UNITED STATES PATENT OFFICE.

FRANK S. CROWELL, OF TOLEDO, OHIO, ASSIGNOR TO THE EDWARD N. RIDDELL COMPANY, OF TOLEDO, OHIO, A CORPORATION OF OHIO.

LIGHTING FIXTURE.

Application filed January 8, 1925. Serial No. 1,155.

My invention relates more particularly to that class of lighting fixtures which are used on porches or exteriors of buildings. It will be apparent from the hereinafter contained description that it is equally useful in interior construction. My invention has for its object to provide a construction in which machine work is practically eliminated and which is so constructed that it will 10 shed water and greatly decrease the amount of snow which would lodge on the fixture, and to provide a construction in which, that even if snow does lodge on it when it melts, it will be unable to interfere with the operation of the fixture.

My means of accomplishing the foregoing objects may be more readily understood by having reference to the accompanying drawings which are hereto annexed and made a 20 part of this specification in which—

Fig. 1 is a front elevation of a lighting fixture constructed in accordance with my improvement.

Fig. 2 is a vertical sectional view taken on the line 2—2 in Fig. 1 in the direction indicated by the arrows.

Fig. 3 is a cross sectional view taken on the line 3—3 in Fig. 2 in the direction indicated by the arrows.

Fig. 4 is a view of the plate, the lamp support being omitted.

Similar reference numerals refer to similar parts throughout the entire description. As shown in the drawings, my invention

comprises a plate 1, which is provided with an aperture 2, and a depression or recess 3, which is formed with a downwardly depending V shaped portion 4, and two laterally extending horizontal portions 5 and 6. In the

wall in the recess adjacent the lower edge of the aperture 2 is an opening 7. In the wall 8 adjacent the upper edge of the aperture 2 is mounted a screw 9. In manufacturing the device I have found it desirable to cast this

screw in place, thus avoiding the necessity of drilling and tapping the hole in the wall 8 in which the screw 9 is mounted. The socket supporting member comprises a downwardly depending portion 10 of inverted truncated

conoidal contour and a circular lip 11. Two stud bolts 12 are cast in lugs formed in the socket supporting member and are adapted to hold in place the porcelain socket 13, the latter being secured in place by means of

nuts 14. In this way all necessity of drilling and tapping holes for screws or bolts 12 is avoided. The socket supporting member is provided with a laterally extending lug 15, which is fitted to and coincides with the V shaped portion 4 and the lateral portions 5 and 6 of the recess 3. A slot 16 is formed in the wall of the lug 15 and is fitted to a screw 17 mounted in the hole 7, a nut 18 serving to hold the screw in position. This slot obviously can be cast in the lug 15, so there is no necessity of any machine work upon it. I provide a cover for the socket supporting member which comprises a conoidal portion 19, which is provided with a radially extending flange 20, the outer edge of which is provided with a downwardly depending flange 21, which extends down beyond the top of the lip 11 of the socket supporting member. The periphery of the flange 21 is inclined outwardly. A laterally extending lug 22 is formed on the cover. This lug is provided with an upwardly extending portion 23, which has a slot 24 cast or formed therein which is fitted to the screw 9. I have found it desirable in practice to form shoulders 25 on the wall of the lug 23 adjacent the ends of the wall forming the slot 24 to prevent the head of the screw 9 from slipping off even if it were slightly loosened.

The fixture is assembled in the following manner:

Screws 17 and 9 are loosely mounted in their places. The slot 16 in the wall of the lug 15 is inserted under the head of the screw 17, when by tightening the nut 18, the lug 15 will be drawn into engagement with the shoulders of the recess 3, so that it is securely held from displacement, and all that the screw does is to hold it from tipping downwardly. The socket 13 is then placed upon the stud bolts 12 and the nuts 14 are tightened down drawing it into position. The lug 22 is then passed through the aperture 2 formed in the plate 1, and the walls 23 are inserted under the head of the screw 9, which passes into the slot 24, until it is beyond the shoulders 25, when by tightening the screw 9 it will tip the cover down causing a very tight fit between the lower surface of the flange 20 and the lip 11. In the preferred form illustrated, I provide a raised boss 30, which affords ample room for the screws 17 and 9 and the end of the lug

22, without coming in contact with the wall of the building to which the fixture is attached.

The result of this construction is that the 5 socket and wiring are completely enclosed, and consequently, water-proof. By projecting the flange 21 beyond the lip 11, water is prevented from beating up into the socket-sustaining portion, and by providing for the 10 slight inclination of the periphery of this flange, the water which is shed by the conoidal portion 19 will drip from the outer edge, thus providing additional protection against the possibility of the water reaching 15 the interior of the socket-sustaining member.

Most of the porch lights with which I am familiar have the holes for the securing screws arranged vertically which results in the fixtures being almost always out of 20 plumb. I provide two holes 26 and 27 which are in the same horizontal plane instead of vertical plane, so that by mounting the screws 28 and 29 in them, there is no possibility of the bracket being twisted out of 25 its proper position.

It will be apparent from the foregoing description that I have eliminated all the necessity for high-grade machine labor on the bracket and yet produce a bracket which 30 is even more rigid in its construction where the parts are screwed or fitted together by machine work; also, that I have provided a lighting fixture which is completely waterproof and may be used on the exterior of 35 buildings without weather conditions causing any trouble.

Although I have shown a specific form embodying my invention, it is to be understood that this is only the preferred form 40 and that I do not desire to be understood as limiting myself to the specific details of construction and configuration, except as such limitations shall appear in the hereinafter appended claims.

45 Having described my invention what I regard as new and desire to secure by Letters Patent is:

1. The combination with an apertured plate, of an outwardly extending socket-supporting member, there being a recess in said 50 plate adjacent the lower side of said aper-

ture, a bolt in said recess, a lug on said member fitted to said recess, there being a slot in said lug which is engaged by said bolt, a cover for said member, a downwardly 55 depending peripheral flange on said cover, a screw mounted in the said plate above said aperture, a lug on said cover which extends through said aperture, there being a slot in said lug which engages said screw, shoulders 60 on said lug adjacent said slot to prevent the head of the screw sliding off said lug.

2. The combination with an apertured plate, of an outwardly extending socket-supporting member, there being a recess in said 65 plate, said recess having a central V shaped portion and two laterally extending portions, a lug on said member fitted to said recess, a slot in said lug, a bolt in said recess which holds said lug in said recess, a conoidal 70 cover for said member, means mounted in said plate to hold said cover in position.

3. The combination with an apertured plate, of an outwardly extending socket-supporting member, there being a recess in said 75 plate, said recess having a central V shaped portion and two laterally extending portions, a lug on said member fitted to said recess, a slot in said lug, a bolt in said recess which holds said lug in said recess, a 80 conoidal cover for said member, means mounted in said plate to hold said cover in position, and means on said lug to prevent said securing means becoming disengaged. 85

4. The combination with a plate having a raised boss thereon, there being an aperture in said boss, of an outwardly extending socket-supporting member, there being a recess in said plate adjacent the lower side 90 of said aperture, a bolt in said recess, a lug on said member fitted to said recess, there being a slot in said lug which is engaged by said bolt, a cover for said member, a downwardly depended peripheral flange on said cover, a screw mounted in the said plate above said aperture, a lug on said cover which extends through said aperture, there being a slot in said lug which engages said 95 screw, shoulders on said lug adjacent said slot to prevent the head of the screw sliding off said lug.

FRANK S. CROWELL.
